UNITED STATES PATENT OFFICE.

LOUIS G. SMOCK AND CHARLES H. DILL, OF DANVILLE, INDIANA.

SPARK-ARRESTER.

SPECIFICATION forming part of Letters Patent No. 289,158, dated November 27, 1883.

Application filed May 10, 1883. (No model.)

To all whom it may concern:

Be it known that we, LOUIS G. SMOCK and CHARLES H. DILL, citizens of the United States, residing at Danville, in the county of 5 Hendricks and State of Indiana, have invented certain new and useful Improvements in Spark-Arresters; and we do hereby declare the following to be a full, clear, and exact description of the invention, such as will enable 10 others skilled in the art to which it appertains to make and use the same.

This invention relates to certain new and useful improvements in spark-arresters for locomotive and other engines, and has for its 15 object the protection of combustible material from the ravages of fire produced by sparks escaping from smoke-stacks and flues, and also to protect travelers in passenger-cars from dust and cinders flying from the smoke-stacks 20 when the doors and windows of the cars are opened; and to this end the invention consists in novel features of construction and combination of parts, all as will be hereinafter fully described, and set forth in the claims hereto 25 annexed.

Referring to the accompanying drawings, Figure 1 represents a side elevation, partly in section, of our improved spark-arrester; Fig. 2, a bottom view or plan of one of the spark- 30 receiving reservoirs.

In the drawings, A represents the smoke-stack of a locomotive or other engine, having at its upper end an enlarged portion, a, which, in connection with the conical cap B, fitting 35 over said enlarged portion a, forms a settling-chamber for arresting the sparks, cinders, dust, &c. The cap B is covered with fine wire-gauze to permit of the passage through it of the smoke from the stack A, and a central 40 tube, b, to which are connected the upper ends

of the conductors C C, which extend downward on opposite sides of the smoke-stack, and are provided with screens c c, to allow any smoke passing down said conductors to escape, while the sparks, cinders, &c., fall into 45 the reservoirs D D, having openings through their bottoms closed by slides d d, through which the dead sparks, cinders, &c., may be drawn off when deemed expedient.

Our improved spark-arrester, while being 50 simple in construction, is efficient in operation, and can be easily and readily applied to the ordinary smoke-stacks of locomotive and other engines.

Having thus fully described our invention, 55 what we claim as new, and desire to secure by Letters Patent, is—

1. In a spark-arrester, the combination, with the smoke-stack A and cap B, covered with fine wire-gauze, of the conductor C, provided 60 near its bottom with a screen, c, and a reservoir, D, below said screen, into which sparks, cinders, &c., are deposited, substantially as and for the purpose herein shown and described. 65

2. In a spark-arrester, the combination, with the smoke-stack A and cap B, covered with fine wire-gauze, of the conductors C C, arranged on opposite sides of said smoke-stack, and provided at their bottoms with screens c 70 c, and reservoirs D D, for the reception of the sparks, cinders, &c., substantially as and for the purpose herein shown and described.

In testimony whereof we affix our signatures in presence of two witnesses.

LOUIS G. SMOCK.
CHARLES H. DILL.
